X-RAY APPARATUS

Willem F. Westendorp, Schenectady, N. Y., assignor to General Electric Company, a corporation of New York

Application June 4, 1937, Serial No. 146,442

3 Claims. (Cl. 250—87)

The present invention relates to high voltage X-ray apparatus, and particularly to improvements in energizing means therefor. While not limited thereto, the invention is especially useful in connection with X-ray tubes adapted to be operated at voltages materially in excess of 100,000 volts.

It is an object of the invention to provide an X-ray apparatus of such inherent characteristics that it draws substantially no apparent power beyond that actually consumed in the generation of X-rays. In connection with this object I have in mind the ultimate end that the power source for the X-ray apparatus and all auxiliary equipment associated therewith may be of small dimensions and economical construction.

It is a further and more particular object of the invention to provide in connection with X-ray apparatus an improved X-ray tube energizing means of such construction that the total current drawn by the apparatus from its power supply source shall contain substantially no inductive or capacitive components attributable to the inherent characteristics of the energizing means.

It is a further object of the invention to provide a voltage transformer suitable for energizing an X-ray tube, in which the lagging or magnetizing current drawn from the supply source by the transformer is substantially equal to and effectively cancels the leading current drawn from the source as a result of the inherent electrical capacity of the transformer windings or of the X-ray apparatus as a whole.

It is a further object to provide X-ray apparatus in which the inductive and capacitive components of wattless power are inherently neutralized without the use of auxiliary circuit elements for accomplishing such neutralization. (By the term "wattless power" I mean the quantity, sometimes called "apparent power", which is represented by the product of a voltage and an out-of-phase component of current produced by such voltage.)

In a preferred embodiment of the invention these objects are attained by providing in the magnetic circuit of the X-ray tube energizing transformer one or more high reluctance or non-magnetic portions whereby the inductive current drawn by the transformer is increased to the same order of magnitude as the capacitive current which it also draws.

The features of novelty which I desire to protect herein will be pointed out with particularity in the appended claims. The invention itself, to-

gether with further objects and advantages thereof, will best be understood by reference to the following description taken in connection with the drawing, in which Fig. 1 is a graphical representation useful in explaining the invention; Fig. 2 is a sectional view of an X-ray apparatus comprising a particular application of the invention; Fig. 3 is a sectional view taken on line 3—3 of Fig. 2, and Fig. 4 represents diagrammatically the equivalent circuit of the construction of Fig. 2.

In connection with most electrical load devices which are supplied with power by means of voltage transformers, the wattless or apparent power drawn by the transformer itself is substantially negligible in comparison with the power drawn by the load device. However, in connection with high voltage X-ray apparatus wherein the transformer is required to supply a current of only a few milliamperes at a voltage materially in excess of 100,000 volts, this is not necessarily true, as will be shown in the following.

The components of wattless power which a transformer draws from a supply line consist primarily of the component corresponding to the magnetizing current of the transformer, and that corresponding to charging current drawn as a result of the secondary winding capacity to ground. The magnetizing power is capable of being predetermined as matter of design and can be maintained at a relatively low value irrespective of the voltages involved. The capacitive or charging power, on the other hand, is not similarly controllable and varies with operating voltage according to the following relationships.

The capacitive power drawn from a supply source by a given transformer can be represented as

$$EI_c = E \frac{1}{2\pi fC} = E^2 2\pi fC$$

where E is the source voltage, C is the effective capacitance of the transformer windings and f is the operating frequency of the source. Thus, for a transformer of given size the capacitive power increases as the square of the voltage applied thereto.

An additional factor is involved, however, in that a substantial increase in voltage rating necessarily implies a proportionate increase in the dimensions (and consequently in the capacitance) of the transformer windings. Correlating this factor with the relationship previously discussed, it may be stated that for transformers

which are similar except for dimensional changes necessitated by variations in voltage rating, the capacitive apparent power will increase roughly as the third power of such rating.

5 The significance of this statement is illustrated in Fig. 1 in which curve A represents the variations of capacitive apparent power with increasing voltage rating. It will be seen that whereas the power may be relatively very small 10 at voltages up to 100,000, it will increase very rapidly at voltages above that value and will have risen about 12,500 per cent at 500 kilovolts. The magnetizing apparent power, on the other hand, will, for conventional transformer designs, vary 15 in the less drastic manner indicated by curve B.

The excess of capacitive power which thus occurs at extremely high voltages is of considerable importance in connection with the operation of 20 X-ray apparatus. For example, in a particular apparatus employing a voltage transformer to energize an X-ray tube at a potential of about 500 kilovolts (peak), it was observed that the wattless power drawn from the power source was about 14 kva. (kilovolt amperes). This wattless power 25 was capacitive in nature and was about 3.5 times as great as the useful power consumed by the X-ray tube itself. Consequently, either a relatively expensive neutralizing circuit element in the form of a reactor had to be provided, or the current-carrying capacity of the power source and the auxiliary supervisory equipment associated therewith had to be made several times as large 30 as the magnitude of the useful load alone seemed to indicate.

35 This difficulty may be overcome in an extremely inexpensive manner in accordance with my present invention, by constructing the X-ray energizing means in such a way that the capacitive power drawn thereby is inherently canceled 40 by the inductive or magnetizing power which it also draws. Specifically, this may be accomplished by including in the magnetic circuit of the X-ray tube supply transformer a high reluctance or non-magnetic portion adapted to increase the 45 transformer magnetizing current to a value commensurate with that of its charging current.

The important features of the invention will 50 probably be most easily understood by referring to the specific embodiment of Fig. 1, wherein I have shown a high voltage X-ray apparatus of the general type disclosed and claimed in an application of E. E. Charlton and W. F. Westendorp, Serial No. 113,862, filed December 2, 1936. As illustrated, this apparatus comprises a metal 55 tank or container 10 substantially filled with an insulating dielectric medium such, for example, as an insulating oil. Immersed in the dielectric medium there is arranged an X-ray tube, shown at the left-hand portion of the figure, and a high 60 voltage transformer for energizing the same.

The X-ray tube comprises a sealed evacuated envelope having a portion projecting exteriorly of the metal container 10 and another portion projecting internally thereof. The externally 65 projecting envelope portion constitutes an anode and includes a target 13 of a refractory metal such as tungsten which is adapted to develop X-rays upon being bombarded with high voltage electrons. This target is provided with external cooling means such, for example, as a cooling coil 14. It is also positioned adjacent a "window" 15 which permits the escape of X-rays in a desired direction. Surrounding the target there is provided a sheath 16 of lead or other X-ray impermeable 70 material, which is grounded to the metallic struc-

ture of the container 10 by being directly mechanically connected thereto.

The portion of the X-ray tube within the casting 10 includes a series of insulating envelope portions 18, an enclosed thermionic cathode 19, and a series of intermediate electrodes 20, of which only two are shown. This portion of the tube is provided with a series of external electrostatic shields 21, each shield being connected to its corresponding intermediate electrode and being so positioned as to decrease the radial electrostatic stress in accordance with the principles set forth in the copending application, Serial No. 113,862, above referred to. Between the shielding members 21 and the X-ray envelope proper there is 15 provided an insulating sleeve 24 adapted to serve as a mounting means for the shielding members.

The X-ray tube construction described in the foregoing is adapted to be energized at voltages materially in excess of 100,000 volts and on the 20 order of 500,000 volts. As an energizing means therefor there is provided a transformer comprising a primary winding 28 and a high potential secondary winding 29. The primary winding, which preferably comprises a helix of copper ribbon, may be connected to an external source of potential (not shown) by means of terminal connections 30, led out through the wall of the metal container 10 in any desired fashion. The secondary winding is grounded at one end to the 30 metal container 10 by means of a connection 33 which may include a current meter 34, and thus is electrically connected to the anode structure of the X-ray tube. The other or high potential end of the secondary coil is connected to the 35 cathode 19 by means of current supply wires 35. As shown, this connection is made within the confines of an electrostatic shielding member comprising a hollow metal toroid 36, such toroid being connected to the high potential terminal 40 of the secondary winding and being so arranged as to enclose the cathode end of the X-ray tube. Intermediate points of the secondary winding 29 are connected to the electrostatic shields 21 by means of conductors 37. The energizing transformer is provided with a magnetic circuit which 45 comprises an iron core 38 having a portion extending within the concentrically arranged transformer windings and insulated from the primary winding 28 by means of an interposed insulating 50 cylinder 39. The core 38 is preferably of laminated construction as indicated in the cross-sectional view of Fig. 3 and may advantageously comprise a rectangular arrangement as illustrated, although other geometrical forms are obviously 55 precluded.

A transformer secondary winding such as that illustrated may, when operated at extremely high potentials and at commercial frequencies, draw a relatively large charging current as a result of the 60 capacity which exists between the various turns of the winding and the grounded walls of the enclosing container 10 and between the shielding member 36 and such walls. In order to compensate or neutralize this charging current, I 65 provide in the magnetic circuit of the transformer core 38 one or more high reluctance of non-magnetic portions. For example, such portions may comprise interposed air gaps or sections of non-magnetic metals or insulating materials. These 70 interposed sections have the effect of increasing the reluctance of the magnetic circuit of the transformer and thereby increasing the transformer magnetizing current to a value commensurate with that of the charging current. Since 75

these currents are of opposite phase with respect to the transformer energizing voltage, they will neutralize one another and substantially reduce the current actually drawn from the power source.

5 From a mechanical standpoint it is convenient to form the non-magnetic sections of a solid material such as a phenolic condensation product and to position them at the meeting points of the various legs of the transformer as indicated at 41, 42, 43 and 44 respectively. This results in 10 a simplified construction by eliminating the customary interleaving of the laminations of magnetic material.

15 The dimensions of the non-magnetic portions depend upon the relative sizes of the other elements of the transformer and upon the operating conditions involved. For any particular case they may readily be determined, either mathematically or empirically, by one skilled in the 20 art. For example, in one instance in which the total length of the magnetic path was about 10 feet and the average cross-sectional area of the path was about .25 square foot, it was determined that the total length of the non-magnetic portions 25 should be about one-eighth of an inch. This determination refers, of course, to a particular X-ray apparatus construction (specifically that shown in Fig. 2 hereof) and would require some modification for different arrangements of the 30 apparatus.

Instead of arranging the non-magnetic portions at the corners of the transformer core as described in the foregoing, it is in some cases preferable to group such sections into a single 35 high reluctance portion (for example, an air gap) arranged at the center of the transformer secondary coil, as indicated at 47 or to provide this in addition to the others. It is an advantage of 40 such an arrangement that any straying of the magnetic flux into the walls of the apparatus container and into other regions of the apparatus as a result of the high reluctance gap is substantially prevented. Furthermore, as an incident of 45 this same factor, the increase in magnetizing current for a given length of gap will be a maximum for a gap arrangement such as is indicated at 47.

The results obtainable by the use of my invention are represented diagrammatically in Fig. 4 which shows an equivalent circuit for X-ray apparatus constructed as described in the foregoing. In this figure the X-ray tube is shown at 49 and the capacitance of the transformer windings is indicated as a condenser 50 arranged in shunt across the X-ray tube. Also in shunt across the X-ray tube and in parallel with the condenser 50 there is shown an inductance comprising a coil 51 and a magnetic core 52 for the same, said core comprising a magnetic circuit which is closed except for the provision therein of a non-magnetic gap 53. If the dimensions of this gap are 55 properly selected (as previously explained herein) the current drawn by the inductance may be made equal to that drawn by the condenser. Since these two currents are opposite in sign, they will neutralize one another as far as external 60 connections are concerned. As a result the power source 55 shown at the left-hand side of the figure will have to be capable of supplying only the current actually consumed by the X-ray tube 49. Furthermore, the metering and control 65 equipment indicated diagrammatically at 56 need be only large enough to handle this relatively small current.

It is a further advantage of X-ray apparatus comprising inductive and capacitive elements which are balanced or tuned as described in the foregoing that there is less distortion of the supply voltage as a result of the pulsating current taken by the X-ray tube. This is a result of 5 the fact that the tuned circuit comprised by the parallel arrangement of inductive and capacitive elements provides an energy storage which is effective to avoid such distortion. From a practical standpoint this avoidance of distortion has 10 the effect of reducing the inverse voltage to which the apparatus is subjected during the non-conductive periods of the X-ray tube, which voltage tends to be increased in proportion to the amount 15 of distortion present.

While I have shown a particular embodiment 20 of my invention, it will be understood that many modifications may be made by those skilled in the art without departing from the invention, and I aim by the appended claims to cover all such modifications as fall within the true spirit and scope of the foregoing disclosure.

What I claim as new and desire to secure by Letters Patent of the United States is:

1. In combination, a metal container enclosing 25 a quantity of dielectric medium, a high voltage X-ray tube immersed in said medium, a transformer also immersed in said medium and having the terminals of its high potential winding 30 connected to the electrodes of the X-ray tube, the electrostatic capacity between such winding and the container being so great that the capacitive current drawn thereby is on the order of or greater than the load current drawn by the X-ray tube, 35 and an iron core for said transformer having a high reluctance portion in its magnetic circuit whereby the inductive current drawn by the transformer is materially increased.

2. In combination, a metal container enclosing 40 a quantity of dielectric medium, a high voltage X-ray tube immersed in said medium, a transformer for supplying said X-ray tube immersed in the medium and having one of its terminals at high potential with respect to the metal container, a 45 shielding member associated with said terminal for modifying the electrostatic field existing between the terminal and the wall of the casing, the electrostatic capacity between the walls of the container and said transformer and shielding member being so great that the capacitive current drawn thereby is on the order of or greater than the load current drawn by the X-ray tube, and an iron core for said transformer having a non-magnetic portion in its magnetic circuit whereby the 50 inductive current drawn by the transformer is materially increased.

3. In combination, a metal container containing 55 a quantity of dielectric medium, an X-ray tube immersed in said medium and intended to be operated at a voltage materially in excess of 100,000 volts, a transformer comprising a primary winding and a secondary winding for energizing said X-ray tube at its intended operating voltage, and an iron core for the transformer having a portion thereof extending through the secondary winding, said core comprising a non-magnetic section within the confines of the secondary winding for materially increasing the inductive current drawn by the transformer during operation.
